UNITED STATES PATENT OFFICE.

GEORGE H. FORSYTH, OF CHICAGO, ILLINOIS.

STRAIN-RESISTING MECHANISM.

No. 923,040.

Specification of Letters Patent.

Patented May 25, 1909.

Application filed January 28, 1905. Serial No. 243,143.

To all whom it may concern:

Be it known that I, GEORGE H. FORSYTH, a citizen of the United States, residing at Chicago, in the county of Cook and State of Illinois, have invented certain new and useful Improvements in Strain-Resisting Mechanisms, of which the following is a specification:

This invention relates to improvements in mechanism for resisting draft and buffing strains, having reference more particularly to such mechanism when employed in connection with railway cars.

The main object of the invention is to provide a draft and buffing mechanism of large capacity and combining the nature and advantages of both the spring and friction forms of draft rigging.

My invention, and the advantages secured thereby, will be readily understood when considered in connection with the accompanying drawings which show practical mechanical embodiments thereof, and in which—

25 Figure 1 is a plan view. Fig. 2 is a longitudinal sectional view of one form of my invention. Figs. 3 and 4 are similar plan and longitudinal sectional views of another form of the invention. Figs. 5 and 6 are 30 similar views, respectively, illustrating the use of followers having reversely curved cooperating surfaces. Fig. 7 is a cross-sectional view on the line 7—7 of Fig. 5. Fig. 8 is a plan view similar to Figs. 1, 3 and 5, 35 but illustrating followers having co-operating surfaces of varying degrees of curvature.

Referring to the drawings, 1 designates the customary center sills of a car, 2 the drawbar, 3 the yoke attached thereto.

40 6 designates a pair of castings riveted to the sills 1 and providing a pocket for the draft-rigging mechanism. 7 designates the end portions of these castings to which are fastened by bolts 10 the supporting runway bars 9 for the spring plates or followers hereinafter described.

In Figs. 1 and 2 the yoke 3 is rigidly attached to the boss of the drawbar 2 by rivets 5. The ends of the yoke 3 are bent inwardly as at 3^a, entering transverse grooves formed between opposed shoulders 2^a and 2^b of the boss of the drawbar.

55 11 designates each of a pair of end followers which at their ends abut against the usual follower stops 8 of the castings 6.

The inner faces of these follower members 11 are formed with curved protuberant or convex surfaces 12 which respectively bear against the outermost plates of two sets of 60 flat spring plates 21. Between these two sets of spring plates is located an intermediate follower member or spacing block 16, the opposed faces of which are inwardly curved or concaved, preferably on substantially the same degrees of curvature as the opposed faces 12 of the end followers 11; so that, under buffing or draft strains the opposed convex and concave surfaces of adjacent followers co-operate to flex the spring 70 plates lying between them.

In the form of the invention shown in Figs. 1 and 2 I provide in advance of the front follower member 11 a block 18 having a convex outer surface 20, between which and the rounded convex end 4 of the drawbar I interpose a set of auxiliary spring plates 22, the ends of this set abutting against curved or inclined surfaces 8^a of the follower stops at the forward end of the castings 6. Preferably I conform the curved surfaces 4 at the end of the drawbar and the surfaces 8^a of the stop lugs so that, when the plates 22 have been fully bowed inwardly of the car under buffing strains, these curves 80 become concentric with each other and uniformly contact with the adjacent surfaces of the spring plates 22. The forward follower member 11 is preferably formed with a central convex protuberant portion 13 which 85 engages a corresponding concave surface 19 of the block 18, which latter has lateral engagement with the edges of the top and bottom members of the yoke by means of the ears 20^a.

The rear portion 14 of the rear follower member 11 is preferably made concave to engage a convex surface 15^a of a block 15 riveted to the end of the yoke, and provided with yoke-engaging ears 15^b. It will be seen that, when the drawbar has been drawn to one side, so as to lie at an angle to the longitudinal median line of the car, these curved surfaces of the follower members 11 and the co-operating blocks 18 and 15 will tend, under the outward thrust of the 105 resistance medium, to impart to the drawbar a self-centering tendency.

While I have shown the spring plates of each group as equal in number, it is evident that they could differ from each other in this respect, as also in respect to the resistance capacity of the individual plates, whereby

one series of spring plates might flex more readily under moderate strains of buffing or draft transmitted thereto, and such an arrangement I have shown in Figs. 3 and 4. In these latter figures I show a construction of car wherein the center sills are located comparatively close together. It will be evident that the spring plates 33, shown in these figures, if horizontally disposed, as in the construction already described, would have to be so short that they would readily tend to set and lose their resiliency. In order that they may be of sufficient length I have shown them as vertically disposed between the end follower members 28 and the intermediate follower member 32. In this form of the invention, the yoke 3 is pivotally connected with the drawbar, this connection being established by means of shorter hollow sleeves 25, which enter within the boss of the drawbar, and through which and washers 26 passes the rivet or pivot-pin 27. The outer ends of the sleeves 25 project somewhat beyond the outer surfaces of the yoke 3, and consequently the heads of the rivets may force the washers 26 hard against the sleeves 25 without binding the yoke 3, thus permitting the drawbar 2 to have entire freedom of angular movement relatively to the yoke 3. I also provide a wearing strip 23 inwardly turned at its forward end, the outer surface of which is convex to conform to the inner concave surfaces of the inwardly turned lips 3^a of the yoke 3, these co-operating concave and convex surfaces being made on the arc of a circle whose center is the axis of the rivet 27. The outer face of the front follower 28 is convex, conforming to the concave surfaces 31 of a block 30 which is held in position by means of a boss 30^a which enters a socket in the end of the drawbar and is secured therein by a rivet 24. Under the outward thrust of the resistance medium of the draft-rigging these convex and concave surfaces co-operate, when the drawbar is drawn to one side, to impart thereto a re-centering tendency.

As shown in Fig. 4, the depth of the yoke 3 is considerably greater than in the construction shown in Figs. 1 and 2, the height of the followers 28 and 32 being made to correspond. Consequently, the depth of the castings 6 is also increased, and the supporting bars 9 are increased, and the supporting bars 9 are upturned and are attached by the bolts 10 to corresponding inclined members 7^a of the end portion of the casting 6.

In Figs. 5 and 6 I have illustrated a modification wherein the end and intermediate follower members 34 and 35 have their proximate surfaces formed with reverse curves made up of alternate convex and concave surfaces 34^a, 35^a and 34^b, 35^b, respectively. The oppositely curved portions of

these reversely curved surfaces may be of the same or varying degrees of curvature, as desired. In the application of buffing and draft strains, the intermediate parts of the spring plates are first bent until the ends of the followers 34 engage the ends of the spring plates, whereupon the latter are then flexed in the opposite direction; this construction affording a draft-rigging capable of a very high degree of elastic resistance.

In the modification shown in Fig. 8 I provide the end and intermediate follower members 37 and 38 with simple curves of varying curvature, the end curves 37^b and 38^b being more abrupt than the intermediate curves 37^a and 38^a. The more moderate strains of buffing or draft afford a gradual and continuous bend to the intermediate portions of the spring plates between the surfaces 37^a and 38^a, whereas the more violent strains, especially those of buffing, impart in addition more abrupt bends in the region of the ends of the spring plates between the curves 37^b and 38^b, thereby greatly augmenting the elastic resistance capacity of the rigging.

It will be seen that one of the advantages of this invention lies in the fact that flat spring plates can be employed, the rate of its increase in spring resistance capacity may be governed according to the kind and degree of the inclination or curvature given to the spring-contacting surface or surfaces of a follower member. A further advantage resides in the fact that the inclines or curves of the follower member may be so limited, proportionally to the thickness or temper of the spring plates, as to prevent any danger of the latter being flexed beyond a point of safety and becoming set, or breaking. Further, it will be understood that various structural modifications may be employed. A still further advantage inhering in the use of two sets of spring plates resides in the fact that each set acts as a motion-reducing device relatively to the other set and the moving follower or followers which operate to flex the same by lessening the extent of movement which said other set undergoes relatively to the movement of the drawbar and yoke, thereby imparting a correspondingly less flexure to said other set of spring plates, with a corresponding decrease in the danger of breaking or "setting" the spring plates.

I claim:

1. In a draft-rigging, the combination with a drawbar and its yoke, of a set of normally straight spring plates, and a pair of followers arranged one on each side of said set of spring plates, said followers having their opposing faces oppositely curved whereby said set of spring plates is engaged at its ends by one of said followers and between its ends by the opposing follower, substantially as described.

2. A buffering mechanism for cars, comprising in combination a draw-bar, draw-bar yoke or extension, followers, front and rear follower stops, a resistance medium between said followers, an auxiliary resistance medium consisting of one or more spring plates interposed between the inner end of the draw-bar and the front follower stops, and a follower block between said auxiliary spring plate or plates and the front follower, substantially as described. 40
5. In a draft-rigging for cars, the combination with follower stops and a draw-bar provided with a yoke, of two sets of spring cushioning plates, a follower interposed between and engaging the ends of said sets of cushioning plates, and front and rear followers acted upon by the yoke and draw-bar, respectively, and centrally engaging the outer sides of said sets of spring cushioning plates, respectively, substantially as described. 45
6. In a draft-rigging, the combination with follower stops and a draw-bar provided with a yoke, of two sets of spring cushioning plates, a follower having wide ends interposed between and engaging the ends of said sets of spring plates, and front and rear followers centrally engaging the outer sides of said sets of spring plates and engaged by the drawbar and yoke, respectively, substantially as described. 50
7. In a draft-rigging, the combination with follower stops and a drawbar and yoke, of two sets of spring cushioning plates, a follower having wide ends interposed between and engaging the ends of said sets of spring plates, and front and rear followers centrally engaging the outer sides of said sets of spring plates and engaged by the drawbar and yoke, respectively, substantially as described. 55
8. In a draft-rigging, the combination with a drawbar and its yoke, of a plurality of sets of normally straight spring plates, followers arranged respectively opposite the outer sides of said sets of spring plates, and an intermediate follower arranged between the sets of spring plates, said followers having their opposing faces oppositely curved whereby each set of spring plates is engaged at its ends by one of said followers and between its ends by the opposing follower, substantially as described. 60
9. In a draft-rigging for cars, the combination with a draw-bar and yoke, of a pair of followers extending across said yoke and engaging stop members carried by the car, said followers having their opposed faces formed on curves of varying degrees of curvature, and spring plates adapted to be flexed between said followers, substantially as described. 65
10. In a draft-rigging for cars, the combination with a draw-bar and yoke, of a pair of followers extending across said yoke and engaging stop members carried by the car, said followers having their opposed faces each formed with reversely curved portions, and spring plates adapted to be flexed between said followers, substantially as described. 70

Correction in Letters Patent No. 923,040.

It is hereby certified that in Letters Patent No. 923,040, granted May 25, 1909, upon the application of George H. Forsyth, of Chicago, Illinois, for an improvement in "Strain-Resisting Mechanisms," an error appears in the printed specification requiring correction as follows: Page 2, line 54, the words "increased, and the support" should be stricken out and the words *located considerably lower* should be inserted instead; and that the said Letters Patent should be read with this correction therein that the same may conform to the record of the case in the Patent Office.

Signed and sealed this 2nd day of November, A. D., 1909.

2. A buffering mechanism for cars, comprising in combination a draw-bar, draw-bar yoke or extension, followers, front and rear follower stops, a resistance medium between said followers, an auxiliary resistance medium consisting of one or more spring plates interposed between the inner end of the draw-bar and the front follower stops, and a follower block between said auxiliary spring plate or plates and the front follower, substantially as described. 40
5. In a draft-rigging for cars, the combination with follower stops and a draw-bar provided with a yoke, of two sets of spring cushioning plates, a follower interposed between and engaging the ends of said sets of cushioning plates, and front and rear followers acted upon by the yoke and draw-bar, respectively, and centrally engaging the outer sides of said sets of spring cushioning plates, respectively, substantially as described. 45
6. In a draft-rigging, the combination with follower stops and a draw-bar provided with a yoke, of two sets of spring cushioning plates, a follower having wide ends interposed between and engaging the ends of said sets of spring plates, and front and rear followers centrally engaging the outer sides of said sets of spring plates and engaged by the draw-bar and yoke, respectively, substantially as described. 50
7. In a draft-rigging, the combination with follower stops and a draw-bar and yoke, of two sets of spring cushioning plates, a follower having wide ends interposed between and engaging the ends of said sets of spring plates, and front and rear followers centrally engaging the outer sides of said sets of spring plates and engaged by the draw-bar and yoke, respectively, substantially as described. 55
8. In a draft-rigging, the combination with a draw-bar and its yoke, of a plurality of sets of normally straight spring plates, followers arranged respectively opposite the outer sides of said sets of spring plates, and an intermediate follower arranged between the sets of spring plates, said followers having their opposing faces oppositely curved whereby each set of spring plates is engaged at its ends by one of said followers and between its ends by the opposing follower, substantially as described. 60
9. In a draft-rigging for cars, the combination with a draw-bar and yoke, of a pair of followers extending across said yoke and engaging stop members carried by the car, said followers having their opposed faces formed on curves of varying degrees of curvature, and spring plates adapted to be flexed between said followers, substantially as described. 65
10. In a draft-rigging for cars, the combination with a draw-bar and yoke, of a pair of followers extending across said yoke and engaging stop members carried by the car, said followers having their opposed faces each formed with reversely curved portions, and spring plates adapted to be flexed between said followers, substantially as described. 70
